UNITED STATES PATENT OFFICE.

ALFRED A. POPE, OF FARMINGTON, CONNECTICUT.

DESIGN FOR A HUB-BAND.

SPECIFICATION forming part of Design No. 35,433, dated December 10, 1901.

Application filed March 11, 1901. Serial No. 50,765. Term of patent 14 years.

To all whom it may concern:

Be it known that I, ALFRED A. POPE, of Farmington, in the county of Hartford and State of Connecticut, have invented and produced a new and original Design for Hub-Bands, of which the following is a full, clear, and exact description, reference being had to the accompanying drawing, forming part of this specification, which shows in perspective view a hub-band embodying my design.

The leading feature of my design consists in a hub-band having near its outer end a grooved portion extending around its circumference and constituted by a series of parallel grooves, at the outer end of which is an annular border extending around the hub, and at the inner end of which is a plain portion 6, into which the rear ends of the grooves disappear.

In the drawing, 2 is the hub-band, and 3 is

the grooved portion, constituted, as above stated, of a series of parallel grooves which extend lengthwise of the hub and form a depressed pattern.

4 is a border at the outer end of the grooved portion 3, and 6 is a plain portion the surface of which is in the plane of the tops of the grooves of the portion 3, the rear ends of the grooves disappearing in said portion 6. In rear of the portion 6 is a portion 5 of somewhat greater diameter.

I claim—

The design for a hub-band, substantially as herein shown and described.

In testimony whereof I have hereunto set my hand.

ALFRED A. POPE.
